UNITED STATES PATENT OFFICE.

GEORGIANNA FAY, OF RICHMOND, VIRGINIA.

NEWSPAPER-WRAPPER.

SPECIFICATION forming part of Letters Patent No. 278,923, dated June 5, 1883.

Application filed May 26, 1882. (No model.)

To all whom it may concern:

Be it known that I, GEORGIANNA FAY, of Richmond, in the county of Henrico and State of Virginia, have invented a new and Improved 5 Newspaper-Wrapper, of which the following is a full, clear, and exact description.

The object of my invention is to provide a new and improved wrapper for newspapers and other like matter, which wrapper can be 10 secured over the paper very rapidly and conveniently without the use of adhesive material.

The invention consists in a wrapper, on the inner surface of which a wire is placed provided with loops at the projecting ends, which wire 15 is held on the wrapper by a strip of paper secured on the inner surface of the wrapper and over this wire. When the wrapper is folded over the paper the projecting ends of the wires are twisted together; or one projecting end of 20 the wire is passed through the loop of the other end.

Reference is to be had to the accompanying drawings, forming part of this specification, in which similar letters of reference indicate corresponding parts in all the figures.

Figure 1 is a plan view of the inner surface of my newspaper-wrapper, parts being broken out. Fig. 2 is an end elevation of the same, showing it partly folded over a paper. Fig. 30 3 is a plan view of a paper surrounded by one of my improved wrappers.

The wrapper A, which is made of paper of any desired or suitable kind, can be made square or oblong, or can have its ends shaped 35 in the same manner as the flaps of an envelope.

A wire, B, is placed across the wrapper from end to end—that is, from flap to flap—on the inner surface of the wrapper, and the ends of the wire are twisted to form loops C at the 40 ends of the wire, the twisted ends of the wire projecting some distance from the ends or flaps of the wrapper, as shown in Fig. 1. A strip,

D, of paper or muslin, is pasted on the inner surface of the wrapper A, over the wire B, for holding the same on the wrapper. The wrapper is passed around the folded newspaper E, or other like matter, and one projecting end of the wire is passed through the end loop, C, of the other end of the wire, and that end of the wire that has been passed through the loop is 50 pressed down flat on the wrapper, and thus holds the wrapper closed on the paper E; or the two projecting ends of the wire can be twisted together for the same purpose. This wrapper can be closed very rapidly and easily, 55 and can be removed very easily in case the contents are to be examined by post-office or custom-house officials; and the wrapper can be replaced and secured without being injured in any way whatever.

A cord may be used in place of the wire, if desired; but the wire is preferred.

Instead of retaining the wire in place by the strip D, the wire may be placed in the body of the paper, such situation being given to it when 65 the paper for the wrappers is manufactured.

Having thus fully described my invention, I claim as new and desire to secure by Letters Patent—

1. A wrapper for newspapers and like matter, consisting of a strip of paper or muslin, to or in which is held a wire the ends of which project beyond the edges of the strip; and which are formed with loops, substantially as and for the purpose set forth.

2. The combination, with the wrapper A and strip D, of paper or muslin, of the wire B, secured between the wrapper A and the strip D, and having loops C at its projecting ends, substantially as and for the purpose set forth.

GEORGIANNA FAY.
